UNITED STATES PATENT OFFICE.

DELBERT L. BARKER, OF PROVIDENCE, RHODE ISLAND.

ARTESIAN OR TUBE WELL.

SPECIFICATION forming part of Letters Patent No. 587,779, dated August 10, 1897.

Application filed May 1, 1897. Serial No. 634,701. (No model.)

To all whom it may concern:

Be it known that I, DELBERT L. BARKER, a citizen of the United States, residing at Providence, in the county of Providence and State 5 of Rhode Island, have invented certain new and useful Improvements in Artesian or Tube Wells; and I do hereby declare the following to be a full, clear, and exact description of the invention, such as will enable others skilled 10 in the art to which it appertains to make and use the same, reference being had to the accompanying drawings, and to letters of reference marked thereon, which form a part of this specification.

15 In a patent of the United States, No. 566,371, issued to me August 25, 1896, I have described and claimed certain improvements in "tube-wells," so called.

20 My present invention also relates to tube-wells, the invention being to some extent an improvement in the art or process of developing tube-wells, as disclosed in the patent referred to, all as hereinafter fully set forth and claimed.

25 I would state here that it is not an unusual condition to find the earth in certain thickly-settled communities stratified with boulders, cobble-stones, gravel, and sand—say within one hundred feet of the surface—in which 30 there is a free circulation of water liable to be contaminated with iron-rust or surface impurities, thus rendering the water discharged from tube-wells located in such districts practically unfit for use, whether employed for

35 culinary or manufacturing purposes. If now the well be sunk still deeper, thereby carrying it down through some stratification, as clay, that is impervious to the surface water, until water-bearing sand is reached, the water

40 thus obtained obviously will be free from the impurities found in the said overlying strata. While it may happen that the volume of water supplied to the wells was ample before the latter were sunken into the sand, the volume

45 of water naturally flowing or percolating into the wells in the latter case would be very much reduced, this being especially true if the sand through which the water percolates be comparatively fine. Under such circumstances it is desirable to supply gravel artificially at the base of the wells to increase

their efficiency or capacity by removing a 55 responding amount of the sand. The said Patent No. 566,371 shows a manner of displacing the sand and forming an artificial bed of gravel in its stead.

In order to effect the result just referred to, it would be impracticable to employ the ordinary appliances as well as being too expensive to supply the wash-water, compressed air 60 or other medium under high-pressure in sufficient volume to cause the sand to flow freely upward to the surface of the ground, because the wash-water or other medium employed would pass off too freely "in circulation" in 65 the different coarse strata of material, instead of returning to the earth's surface.

The object I have in view in my present invention is to provide means adapted to successfully overcome the disadvantages or objections referred to, the result being that a tube-well having any depth and extending downward through any kind of stratifications and terminating in water-bearing sand may have its capacity greatly increased at 70 comparatively small cost, the water of the well being pure or, at least, uncontaminated with surface impurities. I may add that in this country alone there are to-day thousands of 75 large and deep Artesian wells the bottoms of 80 which terminate in water-bearing sand, the yield of water from them being far below the capacity of the tubes. The capacity or productiveness of such wells can be greatly increased by the introduction of large quantities of gravel or other suitable filtering substance around the bottom ends of the tubes, and also whether the latter be provided with screens or have open ends. Such former wells may be thus improved by means of my invention and it can be employed when new 85 wells are being sunk.

By means of my invention the gravel can be sunk and left outside of and around the bottom of the screens even though the latter 95 are somewhat smaller than the inner diameter of the driven or sunken pipe, or good results may be obtained without the use of screens by simply leaving the bottom end of the tube or pipe open, so that water will readily flow therein after first percolating through the gravel.

In the accompanying two sheets of drawings, Figure 1 is a vertical central section of

a well-known form of driven or sunken Artesian well, the pipe thereof passing down through various coarse stratifications and terminating in water-bearing sand, the lower end 5 section of the pipe as drawn being a long tubular screen capable of being withdrawn from the pipe. The several parts are shown in the normal position for use, the pump and some of the minor parts being omitted. Fig. 2 is 10 a similar view of the same, showing the screen combined with my improved apparatus in the act of washing out the sand around the screen preparatory to introducing the gravel. Fig. 15 3 is a similar view showing the artificial filter-bed of gravel practically completed, and Fig. 4 is a sectional view showing the wash-out apparatus removed from the well and the strainer returned to the normal position shown in Fig. 1 and being inclosed in the 20 artificially-formed filter-bed.

Again referring to the drawings, *a*, Fig. 1, indicates an ordinary well tube or pipe sunk into the earth in any well-known manner and extending through various stratifications— 25 as, for example, the surface mold *A*, boulders, coarse gravel, &c., *B*, impervious hard pan or clay formation *C*, and into an indefinite thickness of water-bearing sand *D*. The lower end of the tube *a* has a tubular screen 30 or strainer *s* removably secured thereto, substantially as usual. The bottom end of the tube proper has an external member *b*, of steel, adapted to cut away or loosen the material encountered in sinking the pipe *a*. 35 After the latter has been sunk to the desired depth into the water-bearing sand the tubular screen *s* is inserted in the pipe *a* and forced downwardly into the sand below the end of the pipe. The upper end of the screen, however, rests within the pipe and is kept watertight therein by means of the lead or rubber packing *c*. The latter may be withdrawn or replaced at will by means of suitable connections (not shown) adapted to be attached to 40 the eyes or hooks *d*. The screen itself may be removed by suitable tools or tackle hooked into the bail *s'*, secured to the base of the screen. In lieu of forcing the screen into the sand after the pipe *a* has been sunk into position the two parts may be sunk simultaneously to the desired depth, the lower end of the screen in such case then being, say, flush with the corresponding end of the pipe, after 45 which the latter is lifted until the relation of the parts are substantially as shown in Fig. 1, the impinging force of the sand against the exterior of the screen operating meanwhile to keep it in place or stationary. Assuming now that the pipe and screen have been 50 sunken, say, into water-bearing sand having a degree of fineness such that it quickly impacts itself into and around the screen, (and such conditions are very frequently encountered,) it is obvious that the efficiency or 55 yield of the well is thereby seriously affected. In such case the screen has to be withdrawn at short intervals and after cleaning it is re-

placed at the bottom of the pipe. Under these natural conditions the cost of maintenance is greatly increased, while the yield of 70 water from the well is at best irregular and uncertain.

My invention resides, essentially, in converting an old well, such as before described, or even a new one, into one having a greatly increased yield or efficiency, the change being effected at a comparatively small expense. This is accomplished by first withdrawing the strainer, or it may be a plain tube *s*, and securing at its upper end an internal collar 80 *s'*, into which latter is screwed the central bushing or annular plug *h*, having, say, a left-hand screw-thread. A flanged tube *n* extends down through the center of the plug and screen nearly to the bottom of the latter, 85 the lower end of pipe *n* being secured by a suitable coupling *t* to an open bell-mouthed flexible packing member *o*, of rubber or other suitable material, adapted to bear snugly against the inner surface of the corresponding part of the strainer or member *s*, thus firmly holding the tube *n* in position. After the said tube *n* has thus been secured in place a hollow cone-shaped cap *f* is snugly screwed to the upper portion of the plug *h*, thereby 95 inclosing the tube, &c. The strainer or member *s* is next introduced into the mouth of the pipe *a*, a length of smaller pipe *p* being first secured to the top of the cap *f* by a screw-threaded coupling *m*. The strainer is now 100 lowered to its original place in the sand *D* at the bottom of the well, the pipe *p* at the same time being extended by successive lengths corresponding to the depth of the well. The upper end of the pipe *p* extends above the 105 tube *a* any suitable distance and is provided at the top with a suitable head or stuffing-box *p'*, into which passes a short vertically-movable pipe *e'*, having a branch or nozzle coupled to a hose or connection *e*, communicating with water, compressed air, or other medium under pressure. (See Fig. 2.) Now 110 in order to sink the screen *s* a suitable distance farther into the sand *D* below its original position, (shown in Fig. 1,) water under 115 high pressure, termed "wash-water," is introduced into the pipe *n* of the strainer, (via hose *e*, pipes *e'*, *p*, and cone-shaped connection *f*.) The force of this water expands the said flexible packing *o* snugly against the 120 inside of the screen, thus automatically closing the end of the latter against internal upward currents of water. The action of the wash-water now washes or scours away the sand at the mouth of the screen and at the 125 same time gradually forms an annular passage, as *u'*, upwardly around its exterior until it communicates with the open lower end of the fixed main pipe *a* via the inclined passage *u*. Meanwhile the weight of the screen 130 and its attached parts causes the screen to gradually sink deeper into the sand, thereby at the same time increasing the space or distance vertically between the pipe *a* and con-

nection *f* and forming a practically unobstructed return passage upwardly through the pipe *a* for the waste wash-water and the loosened sand, the said waste water and sand

5 overflowing the mouth of the well-tube at the surface of the ground, where they are allowed to run to waste. This operation is continued until the screen has been sunk to the desired depth or point, when now the pipe *p* and its attached parts are secured in position

10 in any suitable manner. Fig. 2 shows the corresponding relation of the parts before the gravel or filtering material is introduced at the base of the well.

15 In carrying out the part of the invention last referred to I may employ a perforated table or hopper *r* at the mouth of the well, as shown in Fig. 3. After the screen, &c., have

20 been sunk below the tube *a* to the desired depth—say as shown in Fig. 2—the continued flow of wash-water under high pressure from the bottom of the screen or removable tubular section *s* operates to enlarge the space around the latter, the sand thus loosened or disinte-

25 grated flowing upwardly through the well-tube and escaping through the perforated base of the hopper *r*. While this is taking place a suitable quantity of coarse gravel or other suitable equivalent material is shoveled or

30 deposited onto the hopper. The gravel falls by its superior specific gravity downwardly through the ascending column of water and sand to the bottom of the well and gradually fills the space around the screen or section *s*

35 previously occupied by the sand. The operation may be continued until the thus artificially-produced filter-bed *G* of gravel extends quite a distance radially from the screen and even to the base of the well-tube, substan-

40 tially as represented in Fig. 3.

The next operation is to return the movable or screen section *s* to its normal or original position in the base of the tube *a*, and thus exclude all water from the well except that

45 which flows through the screen after percolating through the artificial bed of gravel and the surrounding sand. This operation consists, first, in lifting the screen through the medium of its connections, &c., to the desired

50 height in the bottom of the main tube *a*, the friction of the gravel against the screen meanwhile keeping the latter in position, after which the cone-shaped coupling *f*, feed-pipe *p*, &c., are turned toward the right, thus unscrewing the plug *h* from the nut *s'* of the

55 screen, the latter then remaining stationary, as before stated. The pipe *p* and its attached members are now withdrawn from the well, the central tube *n* and its packing member *o* being also removed with them, since they are

60 all connected together. The said packing-ring *c*, of lead or rubber, is next introduced into the well-tube and forced home into the annular space formed between the adjacent surfaces of the tube *a* and the upper part of the tubular screen or member *s*, thus effectually sealing or closing said space and prevent-

ing water from entering the well except it passes through the member *s*. Fig. 4 shows the thus-completed well.

70 In case the well is not a flowing one the usual pump and connections may be inserted into the well at the proper point, through the medium of which the water then may be forced to the surface, as usual in wells of this type.

75 While I have more particularly described a tube-well having a bottom section, as *s*, adapted to be removably secured thereto even after the main tube *a* has been sunk into the sand *D* to the desired position, I would state

80 that in some wells the bottom or screen sections are omitted altogether and in other cases they are permanently fixed to the open tube *a*. In such instances the yield of water

85 from the wells may be increased, substantially as hereinbefore described—that is to say, the open feed or wash-water pipe *p* is simply lowered to the base of the tube *a* (or to the lower open end of the fixed section *s*, if one be employed,) after which the action

90 of the water or other medium issuing from the bottom of pipe *p* under high pressure washes away or loosens the contiguous sand, and since the practically open annular space

95 between the outer and inner pipes *a* and *p* offers the least resistance to the escape from the well of the waste water the latter, together with the thus-freed sand mingled therewith, flows upwardly to the mouth of the well

100 and runs off to waste, substantially as before stated. Meanwhile the filtering material, as gravel, or, in fact, any other suitable substance—such, for example, as stone, cinders, furnace-slag, hard coal, &c., cracked or broken

105 to the desired size—is gradually introduced into the mouth of the well, the same falling by its superior specific gravity through the ascending column or volume of sand-carrying waste water to the bottom of the well, where

110 it then automatically fills the space previously occupied by the sand, the operation being continued until a filter-bed *G*, having the desired size or capacity, is formed at, around, and below the open end of the fixed tube *a*

115 of the well. After the said artificial filter-bed has thus been produced the feed-pipe *p* may be removed from the well, thus completing the operation, the efficiency of the well thereby having been increased in substantially the same degree as herein first described,

120 wherein the well is provided with a detachable bottom section.

125 I would add that without departing from the spirit of my invention the order or arrangement of the steps employed in the process herein described and claimed may be varied somewhat, and, in fact, some of the steps may be taking place concurrently or simultaneously with another step—as, for ex-

130 ample, the wash-water may be discharging from the pipe *p* while the latter is in motion, thereby at the same time establishing an upward or return current composed of the waste

water and loosened sand carried by it. At the same time, too, the filtering material or gravel may be introduced into the well, thus falling down through and against the force 5 of the said ascending column, or the gravel may be introduced after the sand and water have ceased flowing.

I claim as my invention and desire to secure by United States Letters Patent—

- 10 1. The improved process hereinbefore described of substituting a bed of gravel or other suitable coarse material for a bed of sand or fine material around the bottom of a tube-well located in a water-bearing stratum, which consists in lowering a tubular section or screen to the bottom of the well; then forcing wash-water or other suitable medium under high pressure downward through a smaller pipe secured to said section, thereby washing away sand from the bottom of the section and establishing an upward or return passage around it and between the adjacent walls of the well-tube and the wash-water pipe, through which passage the waste water and the thus-loosened sand flows upwardly to the surface of the ground, the section meanwhile being gradually sunk into the sand until the desired depth is attained; then introducing quantities of gravel or other suitable coarse 25 filtering material into the mouth of the well, from which it (the gravel) falls by gravity to the bottom of the well through the upwardly-flowing current of sand and waste water and around the exterior of the said tubular or screen section, and continuing the last-named step until the desired volume of gravel has been deposited at the base of the well to form an artificial filter-bed; then raising the said movable or screen section until its upper portion is well within the lower end of the main or stationary tube, and sealing it against the entrance of water between the said tube and section, thereby securing the latter in place and insuring that all water flowing into the 40 well must first pass through the lowest or screen section; uncoupling the pipe *p* and cone *f* from the screen *s*, and, finally, in the

case of a non-flowing well connecting the pumping apparatus to the well.

2. The improvement, substantially as hereinbefore described, in the method of increasing the efficiency or yield of water from Artesian or tube wells having their bottom ends open and embedded in water-bearing sand, the same consisting, first, in inserting a smaller 55 or wash-water pipe, *p*, downward into the well to the desired point or distance; next, discharging wash-water or other suitable medium under high pressure from the lower portion of said pipe *p*, thereby loosening the 60 sand, which mingling with the said discharged or waste water flows unobstructedly upward through the annular space between the well-tube and pipe *p* to the surface of the ground and runs off to waste; then gradually introducing the desired volume of gravel or other suitable filtering material, having a greater specific gravity than the water, into the mouth of the well which in falling through the said 65 ascending column of waste water and sand to 70 the bottom thereof fills the space previously occupied by the discharged sand, thereby artificially producing a filter-bed at the base of the well, and finally if desired withdrawing the pipe *p* from the well.

3. In a tube-well of the class described, the combination with the main or fixed tube *a* and a base or screen section, as *s*, adapted to be removably secured thereto, of a wash-water pipe *p* extending into the well, a tube, 80 as *n*, mounted within the said screen-section having a flexible packing at its lower end arranged to bear against the adjacent surfaces of the screen member, and a cone-shaped hollow cap, as *f*, interposed between and secured to the adjacent ends of the screen and pipe members, *s*, *p*, substantially as described.

In testimony whereof I have affixed my signature in presence of two witnesses.
